LENS STRAP MOUNTING

Wayne S. Searles, Providence, R. I., assignor to
 Universal Optical Corporation, Providence,
 R. I., a corporation of Rhode Island

Application February 16, 1935, Serial No. 6,820

13 Claims. (Cl. 88—47)

This invention relates to an ophthalmic mounting, more particularly a strap for a rimless lens; and has for one of its objects the provision of means for compensating for irregular 5 distances of the opening through the lenses from the edge thereof and through which opening the securing screw extends in fastening the strap thereto.

Another object of the invention is the provision 10 of a somewhat flexible but firm support to hold the lens and strap in desired relation.

Another object of the invention is the provision of a firm and yet non-rigid support for a leaf spring which engages the edge of the lens to 15 control the action of this spring and yet itself yield to certain greater pressures prior to rupture of the parts.

Another object of the invention is to divide the 20 resilience between the strap and the edge of the lens into a plurality of parts so that a firm yet flexible support will be had and one in which the resistance may be nicely controlled.

Another object of the invention is the provision 25 of a resilient action in which the resilient parts are divided and may slide one upon the other in controlling the movement of the lens and strap mounted thereon.

Another object of the invention is the provision 30 of resilience between the strap and the lens, which will be entirely controlled through resilient means with no support from the shoe or body portion of the strap.

Another object of the invention is the avoidance 35 of the necessity of a shoe which must be bent to properly engage a spring which in turn engages the lens and the utilization of a resilient self adjusting leaf spring therefor which needs no individual manipulation.

Another object of the invention is the provision 40 of a strap and resilient means thereon which although formed of more pieces than heretofore may be formed as a single unit with no separate pieces for assembly in fitting and adapting the same to the lens.

45 With these and other objects in view, the invention consists of certain novel features of construction, as will be more fully described, and particularly pointed out in the appended claims.

In the accompanying drawing:

50 Fig. 1 is a perspective view illustrating straps mounted at the inner and outer edges of the lens and embodying my invention;

Fig. 2 is a sectional view through the strap and the spring and showing a fragmental portion 55 of the lens as related thereto;

Fig. 3 is a sectional view similar to Figure 2, showing a lens of a somewhat different shape;

Fig. 4 is a sectional view through the strap with the springs omitted;

Fig. 5 is a perspective view of one of the 5 springs;

Fig. 6 is a perspective view of another of the springs;

Figs. 7, 8 and 9 are sectional views similar to Figures 2 and 3 illustrating modified forms of 10 spring arrangements.

In the mounting of a strap upon a lens, it is frequent for the distance from the screw opening in the lens to the edge of the lens to vary in different lenses, and in order to compensate for 15 such variation, a spring take-up is used by positioning a leaf spring along the edge of the lens and between the edge and the strap, which also serves the useful purpose of providing a tension upon the securing screw which extends through 20 the arms of the strap and the lens; and in order that this pressure may be increased for a firmer securing of the parts together and yet a non-rigid construction provided retaining its resilience and affording a greater scope of flexibility, 25 I have provided two or more springs between the strap and the lens, with the longer spring engaging the lens, and the shorter, stiffer spring formed on the arc of a different and shorter radius to engage this longer spring so that its ends will 30 engage just inwardly from the ends of the longer spring and support this longer spring, leaving the portion of the longer spring extending beyond the ends of the shorter for greater flexibility and 35 softer action on the lens and yet reinforcing the general length of the longer spring to such an extent that a very firm support is provided, and yet one which is not rigid but will give, should severe or excessive strains be brought to bear 40 upon the parts, by which construction the springs do the complete supporting without use of any rigid portion of the shoe whatsoever and thus without the necessity of individual manual adjustment by bending of the rigid shoe each time a 45 different lens is positioned in the strap; and the following is a more detailed description of the present embodiment of this invention, illustrating the preferred means by which these advantageous results may be accomplished:

With reference to the drawing, 10 designates 50 a lens of the rimless type to which there is secured at the inner edge a strap 11 having a bridge 12 secured thereto and at its outer edge a strap 13 having a temple 14 secured thereto.

These straps 11 and 13 are of substantially the 55

- same construction as to their portions engaging the lens, and each consists of a body portion 15 with opposite arms 16 and 17 provided with openings 18 and 19 to align with opening 20 in the lens and receive a threaded pin or screw 21 through these openings with the screw threads engaging corresponding threads in the opening 18 in the arm 16 which is located at the back of the lens.
- 5 10 This body portion is provided with extensions 23 and 24 forming a portion of the usual shoe with the inner surface 25 flat or located in substantially a single plane, affording a broad support for the spring when under heavy compression. A stud 26 protrudes from the center of this surface.

20 25 Two springs 27 and 28 are positioned one on the other, each being provided with an opening as at 29, 30, for the reception of a stud 26 which is headed over as at 31 to retain the spring in assembled position on the strap. The spring 27 and spring 28 are also notched as at 32, 33, to provide abutment shoulders 34 and 35 to receive the arms 16 and 17 of the body and assist in preventing rocking of the spring about the stud 26 as a center. The spring 27 is on the arc of a circle of a shorter radius than the edge 36 of the lens, so that its end portions 37 will engage the lens and it will be flexed as the lens is moved 30 towards the surface 25 to align the opening 20 in the lens with the openings 18 and 19 in the arms.

30 35 The spring 28 is shorter than the spring 27 and is on an arc of shorter radius than the spring 27 having its end portions 38 engaging the spring 27 at points inwardly from the ends thereof. The spring 28 is also tempered to be more rigid or stiffer than the spring 27 so that the points of engagement at 38 will firmly support this spring 40 45 centrally and designedly, permitting more resilience of the spring 27 between the end 38 of the spring 28 and the point 37 of engagement of this longer spring 27.

45 50 As these springs being both acute and the surface 25 flat or in a single plane, no spaced supports whatsoever are derived from the body, but an entirely flexible support is provided which is firm and yet should sufficient excess strain be exerted will offer some give prior to breakage. Further, these springs will slide one upon the other, and by being split up into several parts will give a greater flexibility and at the same time a greater support or firmness than is possible by a single spring which might be inserted 55 between the strap and the edge of the lens.

55 60 In Figure 7, I have shown a plurality of three leaf springs, 40, 41 and 42, with the same general scheme of arrangement as illustrated in the preceding figures, that is, each spring is progressively shorter as it is more distant from the lens, and each is progressively on the arc of a shorter radius and also each is progressively stiffer than the spring nearer to the lens to carry out the action above recited.

65 70 In Figure 8 I have illustrated spring 43 and spring 44 as extending in one direction only from the middle, which might for some purposes serve the intended desire. In this case a rigid finger 45 is formed for a support on one side of the strap.

70 75 In Figure 9 I have illustrated an inverted arrangement that is in this case the shorter spring 46 is nearest the lens and the springs are progressively longer as at 47 and 48, as they are more distant from the lens. In this case also, the springs are of an arc of shorter radius progres-

sively, as they are more distant from the lens so as to support the ends of the next inner spring. These ends will not themselves also engage the edge of the lens.

5 The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In an ophthalmic mounting, a lens, a lens strap having a body portion and a pair of arms to extend along opposite sides of the lens, and a plurality of separate arcuate leaf springs positioned between said body and the lens, the spring near the lens being longer and more flexible than the next spring in contact with it, and extending beyond the ends thereof, said longer spring being curved on an arc of greater radius than the next spring to it.

2. In an ophthalmic mounting, a lens, a lens strap having a body portion and a pair of arms to extend along opposite sides of the lens, and a pair of separate arcuate leaf springs positioned between the body and the lens, the spring in contact with the lens being longer than the other spring and extending beyond the ends thereof, said shorter spring being curved on an arc of 30 shorter radius than the longer spring to contact with the longer spring adjacent to but spaced from its ends.

3. In an ophthalmic mounting, a lens, a lens strap having a body portion and a pair of arms to extend along opposite sides of the lens, and a pair of separate arcuate leaf springs positioned between the body and the lens, the spring in contact with the lens being longer than the other spring and extending beyond the ends thereof, 40 said shorter spring being stiffer and curved on an arc of shorter radius than the longer spring to contact with the longer spring adjacent to but spaced from its ends.

4. In an ophthalmic mounting, a lens, a lens strap having a body portion and a pair of arms to extend along opposite sides of the lens, said body having a dimension along the edge of the lens no greater than the largest dimension parallel thereto across one of said arms, means extending through the lens and arms for pivotally connecting the strap to the lens, and a plurality of separate arcuate leaf springs positioned one overlying the other with the end portions of one spring engaging the edge of the lens, said springs 55 when free from distortion influences being on arcs of radii differing in an amount greater than the thickness of said spring with the ends of the overlying spring contacting the underlying spring and held in compression between said body and the lens and tending to move the said body away from the edge of the lens.

5. In an ophthalmic mounting, a lens, a lens strap having a body portion and a pair of arms to extend along opposite sides of the lens, said body 65 having a dimension along the edge of the lens no greater than the largest dimension parallel thereto across one of said arms, means extending through the lens and arms for connecting the strap to the lens, and a plurality of separate arcuate leaf springs positioned one overlying the other and held in compression between said body and the lens, said springs being progressively graduated in length and when free from compression on arcs of radii differing in an amount 70 75

greater than the thickness of said spring with the ends of the overlying spring contacting the underlying spring.

6. In an ophthalmic mounting, a lens, a lens strap having a body portion and a pair of arms to extend along opposite sides of the lens, said body having a dimension along the edge of the lens no greater than the largest dimension parallel thereto across one of said arms, means extending through the lens and arms for connecting the strap to the lens, and a plurality of separate arcuate leaf springs positioned one overlying the other and held in compression between said body and the lens, said springs being progressively graduated in length with the longest spring in contact with the edge of the lens, and the shortest spring in contact with said body, said springs when free from compression being on arcs of different radii with the shortest spring having the arc of shortest radius and the longest spring having the arc of longest radius.

7. A lens strap having a body portion and a pair of arms to extend along opposite sides of the lens, said body having a dimension along the edge of the lens no greater than the largest dimension parallel thereto across one of said arms, and a plurality of separate arcuate springs positioned one overlying the other, means for unitarily assembling said springs with and between said arms, said springs when so assembled and free from compression of the lens being on arcs of radii differing in an amount greater than the thickness of said spring with the ends of the overlying spring contacting the underlying spring.
8. A lens strap having a body portion and a pair of arms to extend along opposite sides of the lens, said body having a dimension along the edge of the lens no greater than the largest dimension parallel thereto across one of said arms, and a plurality of separate arcuate springs positioned one overlying the other, means for unitarily assembling said springs with and between said arms, said springs when so assembled and free from compression of the lens being on arcs of radii differing in an amount greater than the thickness of said spring with the ends of the overlying spring contacting the underlying spring and with their points of contact when free from compression being progressively nearer to the center of the body portion of the shoe.

9. In an ophthalmic mounting, a lens, a lens strap having a body portion and a pair of arms to extend along opposite sides of the lens, means extending through the lens and arms for pivotally connecting the strap to the lens, and a plurality of separate arcuate leaf springs positioned one overlying the other with the end portions of one spring engaging the edge of the lens, said springs when free from distortion influences being on

arcs of radii differing in a greater amount than the thickness of said spring with the ends of the overlying springs contacting the underlying spring and held in compression between said body and the lens and tending to move the said body away from the edge of the lens.

10. In an ophthalmic mounting, a lens, a lens strap having a body portion and a pair of arms to extend along opposite sides of the lens, means extending through the lens and arms for connecting the strap to the lens, and a plurality of separate arcuate leaf springs positioned one overlying the other and held in compression between said body and the lens, said springs being progressively graduated in length and when free from compression on arcs of radii differing in a greater amount than the thickness of said spring with the ends of the overlying springs contacting the underlying spring.

11. In an ophthalmic mounting, a lens, a lens strap having a body portion and a pair of arms to extend along opposite sides of the lens, means extending through the lens and arms for connecting the strap to the lens, and a plurality of separate arcuate leaf springs positioned one overlying the other and held in compression between said body and the lens, said springs being progressively graduated in length with the longest spring in contact with the edge of the lens, and the shortest spring in contact with said body, said springs when free from compression being on arcs of different radii with the shortest spring having the arc of shortest radius and the longest spring having the arc of longest radius.

12. A lens strap having a body portion and a pair of arms to extend along opposite sides of the lens, and a plurality of separate arcuate springs positioned one overlying the other, means for unitarily assembling said springs with and between said arms, said springs when so assembled and free from compression of the lens being on arcs of radii differing in a greater amount than the thickness of said spring with the ends of the overlying springs contacting the underlying spring.

13. A lens strap having a body portion and a pair of arms to extend along opposite sides of the lens, and a plurality of separate arcuate springs positioned one overlying the other, means for unitarily assembling said springs with and between said arms, said springs when so assembled and free from compression of the lens being on arcs of radii differing in a greater amount than the thickness of said spring with the ends of the overlying springs contacting the underlying spring, and with their points of contact when free from compression being progressively nearer to the center of the body portion of the shoe.

WAYNE S. SEARLES.
